UNITED STATES PATENT OFFICE.

JOHN W. NETHERCUTT, OF HUNTINGTON, WEST VIRGINIA.

STREET-CROSSING SIGNAL.

1,232,375.

Specification of Letters Patent.

Patented July 3, 1917.

Application filed January 13, 1917. Serial No. 142,271.

To all whom it may concern:

Be it known that I, JOHN W. NETHERCUTT, a citizen of the United States, and resident of Huntington, in the county of Cabell, and in the State of West Virginia, have invented a certain new and useful Improvement in Street-Crossing Signals, and do hereby declare that the following is a full, clear, and exact description thereof.

10 My invention relates to signal devices for controlling, or directing traffic at street corners. As commonly constructed, these devices are provided with four arms which contain the words "Stop" and "Go," the 15 arms being connected to a common shaft and rotated altogether so that two arms facing the same direction exhibit the word "Stop" and two arms at right angles facing the same direction exhibit the word 20 "Go." A deficiency exists in these devices in that they do not take into account the changing direction of travel of a vehicle at a crossing. Thus for illustration, if the traffic north and south is signaled "Stop" and 25 the traffic east and west is signaled "Go" a vehicle traveling west from the east and desiring to turn south will be confronted by the "Stop" signal to south-going traffic. The object of my invention is to provide in 30 a simple and efficient device a traffic signal which will be able to deal with such a condition as that just described, and to this end my invention consists in the apparatus having the construction substantially as hereinafter specified and claimed.

In the accompanying drawings—

Figure 1 is a top plan view of a traffic signal embodying my invention;

Fig. 1^a is a perspective view of the upper 40 part thereof;

Fig. 2 is a side elevation thereof;

Figs. 3, 4 and 5 are, respectively, detail views in top plan, side elevation and bottom plan view of the signal board carrying head;

Fig. 6 is a detail view in side elevation of the supporting standard, or post;

Figs. 7 and 8 are, respectively, plan and side views of the supplemental signal operating arm;

50 Figs. 9, 10 and 11 are, respectively, detail views of the operating handle and locking devices for the main signal arms;

Figs. 12 and 13 are, respectively, detail

views of the handle supporting and attaching clamp.

55

In the embodiment of my invention shown in the drawings, I employ a round vertical standard, or post 5 fixed to and rising from a proper base 25 over which fits the lower portion of a tubular post, or upright 50, 60 said post 50 being rotatable about the supporting post 5 and supporting at its upper end 4, equidistant radiating arms 8 having the ordinary arrangement and carrying the words "Stop" and "Go" so that by rotating 65 the signal-carrying post 50 through a quarter of a circle, or ninety degrees, the signals will be shifted so that "Go" will be exhibited in the direction just previously occupied by the word "Stop." The signal-carrying 70 arms or boards 8 are rigidly, or immovably attached to the rotating post 50, so that they have no motion relative to the latter, or to each other and they are, respectively, attached to radial ribs, or lugs 14 on the sides 75 of a cast head 140 having flanges 3 at top and bottom and projecting downward at its lower end having a square or flat sided shank 13 which is inserted in the correspondingly shaped upper end of the tubular post 80 50 and thereby a proper connection made with the latter.

For turning the arm-carrying post 50, a handle 15 is provided, which at one end is connected with a clamp collar 17 on the post 85 50, said collar having a clamping bolt 19 passing through opposing outwardly projecting arms upon it, and a bolt 21 which passes through a part of the handle lying between said arms, and which forms a 90 pivotal support for the handle 15 on which it may swing vertically so as to place a latch lug 16 carried on the underside of the handle into and out of engagement with locking slots, or notches 24 and 26 provided, 95 respectively, in the supporting standard 5, and the post 50. The slots 24 are ninety degrees apart and by the turning of the standard 50 the slot 26 in the side of the latter may be placed in alignment with either 100 of said slots 24, and when so aligned and the lug 16 is passed through them, the standard 50 is locked from rotating. At its inner end the handle 15 has a hook 18 adapted to engage the clamping bolt 19 when the handle 15 is in a horizontal position and thus main-

tain the latter in that position, and the sliding movement of the handle 15 is necessary to first disengage the hook 18 from the bolt 19 when it is desired that the locking lug 5 16 shall enter the alining slots 24 and 26. A slot 20 is provided in the handle 15 through which passes the pivot bolt 21 that allows the longitudinal movement of the handle necessary to disengage it from the 10 clamp bolt 19 and to reengage it therewith.

Besides the signal carrying arms 8, which are rigidly and immovably attached to the post 50, there are four supplemental signal-carrying arms 7 which are pivoted so that 15 they may swing from a position lying intermediate an adjacent pair of stationary arms 8, which is a non-indicating position, to a position lying over the word-carrying side of the stationary arm 8 to enable the 20 substitution for the word exhibited by such stationary arm of a contrary word which is carried on the swinging arm 7, as for example, the substitution of the word "Go" or "Turn" for "Stop" and the substitution of the 25 word "Stop" for "Go" or "Turn." The arms 7 are connected so as to swing simultaneously in pairs, the two arms thus connected in a pair being ninety degrees apart, and they are so connected by an angle lever 2 which at its 30 elbow, or angle is mounted on the arm pivoting rod 11 and at its outer end each lever arm has a pin and hole connection with the appropriate signal bearing arm 7, which pin and hole connection in one instance is one 35 in which the hole has the form of a slot 10 because the arm 7 thus connected with the lever 2 is pivoted eccentrically to said angle lever. The pivoting rods 11 to which the angle levers 2 are, respectively, connected, 40 are carried downward alongside the post 50 and at a convenient height for reaching by the operator are extended outwardly to form for each a handle 23 by the manipulation of which the supplemental signals are 45 actuated. As will be evident both the main and the supplemental signals being carried by the rotatable post 50 all turn together when the handle 15 is operated. The device for latching the post 15 against turning is 50 desirable in order that it may remain stationary when the supplemental carrying arms 23 are turned. It will be seen that by means of my supplemental signs it is possible so to control traffic that a vehicle not 55 desiring to continue onward past a crossing in the same direction in which it approaches, but for example desiring to turn south after coming to the crossing from the east, may be signaled so to do and traffic that would 60 otherwise interfere can be held in check.

Preferably the operating handles are so arranged with reference to the signals that they point, or extend in the direction in which traffic flows, or moves.

The operation of the signal apparatus 65 shown may be illustrated as follows: Suppose the main signal arms 8 are turned to a position for stopping traffic north and south and releasing it east and west, and a vehicle approaches from the east which 70 desires to turn south. To signal such a vehicle that it may turn south the supplemental arm 7 bearing the word "Turn" is swung from the north position shown in Fig. 1 of the drawings where it covers the "Stop" 75 signal of the stationary arm 8 to uncover that signal, to the position to cover the "Stop" signal that arrests southward traffic, and displays thereat the signal "Turn", and at the same time the supplemental signal arm 7 connected therewith by the angle lever 2 is swung to place "Stop" over the "Go" signal of the south signal-carrying arm 8, thus stopping eastward traffic. As soon as the vehicle makes the turn to the 80 south the pair of supplemental signal arms 7 just referred to, will be moved to their former positions, thus exposing the signal "Go" on both sides and in both directions 85 east and west.

For the more convenient understanding of the arrangement shown in the drawings on Fig. 1, the words "Stop" "Go" and "Turn" are printed to designate those sides of the arms 7 and 8 which carry these words, and also the initials of the four points of the compass are noted to elucidate the operation 90 above described.

Having thus described my invention what I claim is—

1. A traffic signal comprising a plurality of signal-carrying members, means for changing their signaling position, and a supplemental signal-carrying member movable to and from a position to cancel the 105 signal of one of the other signal-carrying members, the canceling and the canceled signals having different significations.

2. A traffic signal comprising a plurality of signal-carrying members, a rotatable support upon which they are mounted from which they radiate in four directions, and a supplemental signal-carrying member shiftable to and from a position where it serves as a substitute for the signal on one 110 of said other signal-carrying members, there being one of said supplemental signal carrying members for each of said other signal-carrying members.

3. A traffic signal comprising a rotatable 120 support, four signal-carrying arms fixedly mounted on said support and radiating therefrom in different directions, four supplemental signal-carrying arms, and means for swinging said supplemental signal carrying arms in pairs to substitute their signals for those on an adjacent pair of the main signal-carrying arms.

4. A traffic signal comprising a rotatable support, four signal-carrying arms fixedly mounted on said support and radiating therefrom in different directions, four supplemental signal-carrying arms, and means for swinging said supplemental signal-carrying arms in pairs to substitute their signals for those on an adjacent pair of the main signal-carrying arms, said supplemental arms and their operating means also being carried by said rotatable support.
- 5 In testimony that I claim the foregoing I have hereunto set my hand.

JOHN W. NETHERCUTT.
